COMBINATION TOOTHPASTE AND TOOTHBRUSH HOLDER

Albert H. Aul, Chicago, Ill.

Application March 16, 1955, Serial No. 35,056

Term of patent 3½ years

(Cl. D4—3)

Fig. 2

Fig. 1

Fig. 3

Fig. 5

Figure 1 is a front elevational view of a combination toothpaste and toothbrush holder showing my new design;

The toothbrush and tube shown by means of broken lines in Figure 1 are disclosed only for illustrative purposes.

I claim:

The ornamental design for a combination toothpaste and toothbrush holder, as shown and described.
